R. M. SHARAF

TRIMMING OR CUTTING MECHANISM FOR SEWING MACHINES

Filed April 2, 1917

Fig. 1.

UNITED STATES PATENT OFFICE.

RALPH M. SHARAF, OF NEW YORK, N. Y., ASSIGNOR TO R. M. SHARAF MACHINE CO., OF BOSTON, MASSACHUSETTS, A CORPORATION OF MASSACHUSETTS.

TRIMMING OR CUTTING MECHANISM FOR SEWING MACHINES.

Application filed April 2, 1917. Serial No. 159,059.

To all whom it may concern:

Be it known that I, RALPH M. SHARAF, a citizen of the United States, and a resident of the borough of the Bronx, in the city and State of New York, have invented certain new and useful Improvements in Trimming or Cutting Mechanism for Sewing Machines, of which the following is a specification.

10 The present invention relates to improvements in trimming or cutting mechanisms for sewing machines, and particularly such sewing machines of the two needle type, an object of the invention being to provide means in advance of the feeding and sewing elements for cutting out a strip of cloth, lace or other auxiliary fabric being sewn into the cut out portion. A further object is to provide such means which will 15 be operated by the feeding mechanism to the end that an accurate and properly timed cutting takes place. It is also an object to provide such cutting means which by reason of their simplicity of construction and attachment, may be readily removed and sharpened without the necessity of putting the machine out of operation for any material length of time, and without requiring the services of an expert.

20 30 It is also proposed to provide in connection with the cutting means, and edge trimming device by means of which a novel method of connecting the auxiliary fabric to the main fabric may be carried out, and as a result of which, a secure, neater and more desirable product may be obtained than is possible by the methods at present in use.

With these and other objects in view, an embodiment of my invention is shown in 35 the accompanying drawings, which invention will be hereinafter more fully pointed out in the claims.

In the accompanying drawings;

Figure 1 is a side elevation of the presser foot and cutting means, partially broken away,

Figure 2 is an end view thereof,

Figure 3 is a plan view of the same,

Figure 4 is a perspective view of the 50 knife support, and knives detached from the machine,

Figure 5 is a diagrammatic view of the cutting knife, folding guide and needle at one side of the presser foot, and illustrating

the improved method of sewing permitted thereby,

Figure 6 is a perspective view of the same parts, and

Figure 7 illustrates the resulting stitch and connection of the material.

Similar reference characters indicate corresponding parts throughout the several figures of the drawings.

Referring to the drawings, the sewing machine head (not shown) is provided with a presser foot bar 11, a needle bar 12 of the usual construction, and a lace feeding bar 13. The presser foot bar 11 may be raised in the usual manner to permit of the preliminary insertion of the cloth into the same by means of the manual lifting lever.

The lace feeding bar reciprocates preferably by means of the mechanism such as that disclosed in my co-pending application Serial No. 159,057, filed simultaneously here-with, or in my application Serial No. 127,322, filed October 24, 1916.

The presser foot comprises a solid foot portion 16 secured in the bifurcated end 17 of the bar 11 by a screw 18 and extends relatively close to the needles 19. Side plates 20 and 21 are secured at each side of the foot portion by dowels 22 and screws 23, extending at each side of the needles and supporting between the same at the other side of the needle bar 12, a lace guide 25, and a lace keeper 24 secured by screws 25^a and 26^a, the inner curved face of the lace guide block 25 being spaced back from the inner edges of the side plates 20 and 21, so as to form retaining walls to prevent lateral displacement of the lace.

The lace guide block 25 is provided at its outer side with a pair of spaced slots or guideways 26^c and 26^d, the direction of the slots and the outer wall of the block being drawn from a radius with a point 27 of the presser foot bar as a center, and at that point is pivotally secured a pivoted knife support. This support comprises an arcuate arm 28 L-shaped in cross section and provided at its inner end with a bearing 29 which engages a stud 30 secured to the presser foot bar. At its other end there is provided a supporting block 31 extending at an angle from the arm and having slots 32 and 33 therein in circular alignment with the slots 26^c and 26^d of the lace guide block. A pair

of elongated blades 34 and 35 are secured in the said slots 32 and 33 by a removable plate 36 and a screw 37; these blades extending downward through the slots 26^e and 26^d and being provided at their lower ends with inclined knife edges 38 adapted to be brought above and below the throat plate of the machine as the knife support is oscillated in a manner to cut out a strip 10 of cloth prior to the sewing of the lace to the cloth. A cover plate 39 is secured to the back of the block 24 to close the slots 26^e and 26^d and extend slightly over the support block 31 so as to guide the same in 15 its movement.

In order to bring about the oscillation of the knife support, I provide a lever 40 slotted at its ends 41 and 42 and pivoted upon a stub shaft 43 secured to the plates 20 and 21, 20 the lever being exterior of the plate 20. The end 41 engages a pin 44 provided upon the lace feeding bar 13, while the other end engages a pin 45 mounted between the pair of lugs 46 and 47 provided on the end of the 25 arm 28. Thus it will be seen that the downward movement of the lace feeding bar causes the knife blades to be raised out of engagement with the cloth, as clearly illustrated in dot and dash lines (Fig. 1) permitting the feeding of the cloth and lace to 30 take place unhampered. At the end of the feeding operation and upon raising of the lace feeding bar, the blades are disposed as shown in full lines in Figure 1, thereby cutting 35 out the strip of cloth. The curved and inclined cutting edges, together with the movement of the blades in a circular arc results in a clean and positive cutting of the material, the strip of material cut being 40 narrower than the lace.

The knives may be accurately adjusted or removed when desired for replacing or sharpening by simply removing the plate 36 by means of the screw 37. The operation is 45 positive and exactly timed with the movement of the feeding mechanism.

The lace or other auxiliary material to be secured to the edges of the material from 50 which the strip is cut, is fed along the block 25 beneath the keeper spring 24 by means of the serrated blade 13^a of the reciprocating lace feeding bar 13, the end of the blade engaging the lace in its upper position at a distance above the lower extremity 55 of the block corresponding to the amount of lace to be fed for each sewing operation, the down movement of the bar 13 moving the blade to the lower extremity of the block. The keeper 24 prevents any picking 60 up of the lace upon the upward movement of the feeding bar. The other material is preferably fed by a plurality of independently movable dogs, this mechanism and the lace feeding mechanism being preferably of the 65 type disclosed in my co-pending applica-

tion Serial No. 159,057, filed of even date herewith, entitled "Feeding mechanism for sewing machines."

In Figures 5 to 7, I have illustrated the improved method of sewing the selvedge of the lace to the edges of the body material. The two needles 50, (Fig. 3) which are positioned in front of the knives, have a zig-zag movement, which may be brought about by any approved mechanism for this purpose, the needles either moving simultaneously in opposite directions, or toward and away from each other. The cloth 51 has a strip cut therefrom prior to the sewing operation, and the lace 52 is fed thereon, as clearly shown in Figure 6, so that its selvedge 53 overlaps the cut edges of the cloth.

A cloth folding guide is arranged between the cutting blades adjacent the needle and projects downwardly in a vertical plane on a transverse line between the points, the blade acts on the cloth at the stitching point. This guide bears against the raw edge of the cloth first previously formed by the cutting device, and folds the same downwardly through about 90 degrees, as illustrated at 55, thereby holding this edge outside of the point of the needle, while it is making its down stroke indicated in dotted lines (Fig. 5). In its zig-zag movement the needle reciprocates to and fro from points just inside of the outer line of the folded under edge of the cloth, to points inside of the line on which the cloth has been folded, see Fig. 7. The lower thread 56 which is looped by the thread 57 of the needle by means of the shuttle hook 58, is drawn up tightly upon the upstroke of the needle, completing the folding of the cloth up 95 against the body of the cloth where it occupies a position beneath the selvedge of the lace. The thread from this shuttle forms the stitch with the thread of the needle in both of its positions, as for instance, by oscillating the shuttle or looper synchronously with the needle, as shown in my application No. 159,058 filed April 2, 1917.

The overwhipping of the thread in a manner to completely enclose the fold of the cloth without piercing of the cloth at the folded portion, forms a neat, strong and finished seam. As the edge of the lace is not pierced, the needle in both positions entering the body of the cloth in one case, and the body of the lace in the other case, there can be no tearing or raveling of the fabric. In other words, the superposed selvedge of the lace and folded under portion of the cloth is completely embraced by the stitching, but they are not pierced by the needles, the loops at each side being spaced from the free or outer edge of the fold of the cloth, and from the line on which the cloth is folded. The appearance of this method of sewing is clearly illustrated di- 100 110 115 120 125 130

agrammatically in Figure 6, in which the lace is considered as transparent, and the lace guide is not shown. It will of course be understood that this action of the zigzag stitching is applicable to the sewing of the lace or other auxiliary fabric with the use of one needle only.

I have illustrated and described a preferred and satisfactory embodiment of my invention, but it is obvious that changes may be made therein within the spirit and scope thereof as defined in the appended claims.

I claim:

15 1. In a sewing machine, a presser foot provided with a circularly curved guideway lying in a vertical plane, a trimmer knife movable along said guideway, and an arm carrying said knife and pivoted to swing about a horizontal axis passing through the center from which said guideway is curved.

20 2. In a sewing machine, a guide curved according to the arc of a circle, a knife movable along said guide, and an arm carrying said knife and pivoted to swing about an axis passing through the center of said circle.

25 3. In a sewing machine, a guide curved according to the arc of a circle, a knife of like curvature movable along said guide, and an arm carrying said knife and pivoted to swing about an axis passing through the center of said circle.

30 4. In a sewing machine, a member having a guide slot curved according to the arc of a circle, an arm pivoted to swing about an axis passing through the center of said circle, a holder on said arm, provided with a slot of the same curvature as said guide slot and in alignment therewith, and a knife carried by said holder and adjustable in the slot thereof, and extending into said guide slot.

35 5. In a sewing machine, a presser foot provided with an upright circularly-curved guideway, a trimmer knife movable along said guideway, and an arm carrying said knife and pivoted to swing about an axis perpendicular to the plane of said guideway and passing through the center from which said guideway is curved.

40 6. A trimming or cutting mechanism for sewing machines, comprising a pivoted member, a knife supported by said pivoted member, a feed bar movable up and down and having a feed action on its downstroke and inactive on its upstroke, as regards feeding, and means operatively connecting said feed bar to said knife, to impart downward movement to said knife upon the upward movement of said feed bar.

45 7. In a trimming or cutting mechanism for sewing machines, the combination of a

guide provided with slots curved according to circular arcs and disposed in spaced parallel planes, knives cooperating with said slots, said knives being curved and pivotally supported, the center of curvature of said knives of said guide slots being the pivotal point of the knives.

50 8. In a sewing machine, a member having a relatively stationary guide slot curved according to the arc of a circle, a movable holder provided with a slot of the same curvature as said guide and in alignment therewith, a knife carried by said holder having a corresponding curvature to said slots of said guide and holder and adjustable lengthwise in the slot of said holder and extending into said guide slot, and means for moving the knife lengthwise of said guide slot.

55 9. In a sewing machine, a presser foot provided with a guideway curved according to the arc of a circle, an arm mounted to swing about the center of said circle, a knife carried by said arm and movable along said guideway, a lever fulcrumed on the presser foot between said guideway and the center of said circle, and in operative engagement with said arm, and a vertically reciprocating feeding member engaging said lever on the side of its fulcrum opposite to the one where it engages said arm.

60 10. In a sewing machine, the combination with a lace feeding means, a guide curved according to the arc of a circle adjacent the lace feeding means, a curved knife movable along said guide, and means operated by the lace feeding means for moving the knife in said guide.

65 11. In a sewing machine, the combination with a lace feeding means, comprising a lace guiding means, feeding means therefor, a curved guide adjacent the lace guiding means and arranged in the arc of a circle, a curved knife movable along said guide, and means operated by the lace feeding means for moving the knife in said guide.

70 12. In a sewing machine, the combination with a lace guiding and feeding means, comprising a curved guide adjacent the lace guiding means and arranged in the arc of a circle, a curved knife movable along said guide, and means operated by the lace feeding means for operating the knife in said guide and moving it out of cutting position during the feeding of the lace.

75 13. In testimony, that I claim the foregoing as my invention, I have signed my name in presence of two subscribing witnesses.

RALPH M. SHARAF.
